APPARATUS FOR METAL PLATING

Lawrence Greenspan, Bronx, N. Y.

Application September 16, 1950, Serial No. 185,205

8 Claims. (CL. 204—297)

1

This invention relates to improved devices for rapidly and uniformly plating objects, and novel methods of plating the objects. More particularly the invention relates to devices for electro-forming stampers or dies used in the manufacture of phonograph records and electrical transcriptions and methods of making said stampers or dies.

It is the general object of the present invention to provide novel and improved devices and methods for producing stampers rapidly and with a minimum variation in thickness of the electroformed shell or stamper from the center to the periphery.

Another object of this invention is to provide in a plating apparatus of the character described, baffle means to direct plating current inwardly of the periphery of the cathode surface being plated, in order to prevent an excessive build-up of electrodeposited metal at the periphery and thereby produce a plating of substantially uniform thickness.

A further important object of this invention is to provide in plating apparatus of the character to be described, means to direct a stream of gas bubbles through the plating solution and adjacent the cathode surface being plated, in order to produce vigorous agitation of the plating solution and thereby permit the use of high current densities to obtain rapid plating.

Still another object of this invention is to provide in a plating apparatus of the character to be described, baffle means to direct the plating current uniformly over a metallized cathode surface, and means to vigorously agitate the plating solution by passing a flow of air bubbles through the plating solution and adjacent the surface being plated, whereby high current densities may be employed to decrease the plating time.

Another object of this invention is to provide a device for electroforming stampers comprising a backplate made of electrically insulating material chemically inert to the electrolyte, a cathode holder attached at one end to the back of said backplate, said cathode holder having its other end adapted to electrically contact a negative bus bar, and means at the attached end to make electrical contact through said backplate with a metal sheet held against the front of the backplate, means at said attached end to hold the object to be plated in front of said sheet with said sheet extending beyond the periphery of said object, and means to provide a stream of air bubbles through the plating solution and ad-

2

jacent to the surface of the object to be plated during the plating process in order to produce vigorous agitation of the electrolyte over the whole exposed face of said object and sheet, whereby a high current density may be used to obtain rapid plating.

A further object of this invention is to provide in a device of the character to be described, inclined baffle plates forwardly and inwardly and overlapping the outer edges of a metal sheet, adjacent the sides and bottom edges of the backplate, in order to prevent the formation of trees, nodules and roughness along the edges of the surface being plated and to cause the plating metal to deposit uniformly on the object being plated.

Still another object of this invention is to provide in a device of the character to be described, a metal sheet interposed between a chemically and electrically inert backplate and the object to be plated, said sheet extending beyond the edges of said object whereby the plating current is caused to distribute itself uniformly over the object to be plated, and to electrodeposit a shell of substantially uniform thickness without the formation of nodules, trees and roughness which in prior methods had a tendency to form around the periphery of the object being plated.

Still another object of this invention is to provide a device for electroforming stampers comprising a backplate made of electrically insulating material, chemically inert to the electrolyte, a cathode holder attached at one end to the back of said backplate, said cathode holder having its other end adapted to electrically contact a negative bus bar, and means at the attached end to hold and make electrical contact through said backplate with a metallized cathode surface of a record to be plated, means attached to said backplate to provide a stream of air bubbles through the plating solution and adjacent the surface of the record to be plated, and a baffle spaced from said backplate and parallel thereto, and in front of the record surface being plated, said baffle being formed with a hole of smaller diameter than the diameter of the record being plated, whereby the electrodeposited metal is caused to distribute itself uniformly on the metallized cathode surface, and permit appreciable saving in copper.

Yet another object of this invention is to provide an economical method of manufacture of stampers in which a minimum of equipment, space and labor is required.

Other objects of this invention will in part be obvious and in part hereinafter pointed out.

The invention accordingly consists in the features of construction, combination of elements, arrangement of parts, and method steps which will be exemplified in the construction herein-after described, and of which the scope of invention will be indicated in the following claims.

In the accompanying drawings in which are shown illustrative embodiments of this invention,

Fig. 1 is a front elevation view of a preferred embodiment of the invention;

Fig. 2 is a cross-sectional view taken along the line 2—2 of Fig. 1;

Fig. 3 is a top plan view of the embodiment shown in Fig. 1;

Fig. 4 is a top plan view of two units of the embodiment shown in Fig. 1, in a plating tank;

Fig. 5 is a cross-sectional view taken along the line 5—5 of Fig. 4;

Fig. 6 is a view similar to Fig. 1 showing another embodiment of the invention;

Fig. 7 is a top plan view of the embodiment shown in Fig. 6;

Fig. 8 is a cross-sectional view taken along line 8—8 of Fig. 6;

Fig. 9 is an enlarged cross-sectional view of a portion of a phonograph record whose surface has been metallized;

Fig. 10 is a view similar to Fig. 9 showing a portion of the electroformed stamper deposited on the metallized surface; and

Fig. 11 is an enlarged cross-sectional view of a portion of the electroformed stamper deposited on the metallized surface of the record and removed from the record.

In the manufacture of phonograph records and electrical transcriptions there has been a great need for producing an electro-formed shell or stamper which has a smooth surface without trees or nodules, is hard and springy without being brittle, and has a well controlled and constant thickness from the periphery to the center. Also, it is desirable to produce these stampers as rapidly as possible.

In the usual method of producing electro-formed shells or stampers, the original recording disc which is made of wax or aluminum coated with a film of cellulose acetate, on which the recording grooves are cut, is first metallized to make the surface electrically conductive. The conventional methods used are either to apply a gold film by sputtering or to form a silver mirror by spraying or immersion tank methods. This film or mirror is next strengthened by applying a preplate at low current density to build up a shell having a thickness of approximately 0.0005" to 0.001". The record disc is then plated at a higher current density to build up a thickness of approximately 0.050" of metal, usually copper. Obviously, it is desirable to produce these stampers as rapidly as possible and with a minimum outlay of equipment and space. Most of the methods in common use take from 16 to 48 hours to electroform the shell or stamper. Faster plating methods have been devised by rotating the cathode, providing a system of baffles and circulating the plating solution. These methods are comparatively expensive from the standpoint of initial equipment cost, excessive space and maintenance required. Also, in most of the methods in common use the electroformed shells show a variation in thickness of copper, or other metal, of as much as 0.050" from the center to the outside edge. In view of the fact that it is neces-

sary to turn the shells down to a uniform thickness on a lathe, an excessive number of cuts are required to make the stamper of uniform thickness and this makes the process expensive both from the standpoint of labor and loss due to copper scrap. Furthermore, there is a tendency for the outer edges to be cold worked excessively in the cutting operation on the lathe, resulting in a hardening and embrittling action on the outer surfaces and causing distortion and even cracking of the stamper when removed from the cutting lathe. The devices and methods of the present invention for producing stampers overcome all of these disadvantages.

Referring now to the drawings, particularly Figs. 1, 2 and 3, for a more complete understanding of the invention, 10 designates the plating device embodying the invention for electroforming stampers or dies used in the manufacture of phonograph records and electrical transcriptions. The plating device 10 comprises a rectangular support or backplate 11 which may be made of a plate of chemically and electrically resistant material such as "Bakelite," micarta, or similar non-conductor of electricity. Said backplate 11 comprises a front wall 12, a rear wall 13, a top edge 14 and a bottom edge 15. Backplate 11 is further formed with substantially 45° beveled edges 16 extending forwardly and inwardly from the rear wall 13 to the front wall 12. At substantially the center of backplate 11 is a shallow disc-shaped recess 17 in wall 12. Extending rearwardly from recess 17 is a smaller disc-shaped recess 18, concentric with recess 17. Extending rearwardly from recess 18 is a round hole 18a communicating with the rear wall 13 of backplate 11 for the purpose hereinafter described.

To help prevent an excessive build-up of deposited metal around the periphery of the stamper to be formed and to prevent treeing of deposited metal along the edges of the aluminum sheet to be described, there is attached to each beveled edge 16 of backplate 11, by any suitable means such as screws 19, a rectangular sheet or baffle 20. The baffles 20 are made of the same composition as backplate 11, are coextensive with edges 16 and extend forwardly and inwardly of said backplate 11.

Flush with the lower edge 15 and on the front wall 12 of backplate 11 is a rectangular spacer bar 21 of rectangular cross-section and of chemically and electrically inert material similar to said backplate 11. Said spacer bar 21 is attached to backplate 11 by means of screws 23 or any other suitable means. The triangular shaped holes 21a formed between the ends of the spacer bar and baffles 20 are for the purpose of permitting drainage of electrolyte when device 10 is removed from the plating bath.

In order to permit faster plating of the record by use of high current densities with this invention, strong agitation of the plating solution is provided by a steady stream of air bubbles through the solution and over the surface of the record to be plated. To this end, there is provided a member 24. Member 24 may be made of the same composition as backplate 11 and comprises a rear wall 25 contacting the front wall of spacer bar 21 and extending beyond the side edges thereof, a lower horizontal edge 26 flush with the lower horizontal edge of spacer bar 21, a front wall 27 parallel to rear wall 25, and an upper wall 28 sloping downwardly and rearwardly at an angle of substantially 45° from front wall 27 to rear wall 25. Walls 28 and 25

meet in a straight line which is substantially at the level of the upper horizontal edge of spacer bar 21, or slightly above this level. Member 24 may be secured to spacer bar 21 by the screws 28 or any other suitable means. The side edges 29 of member 24 are beveled in the same manner as side edges 16 of backplate 11, and form plane surfaces therewith which contact the inner surfaces of baffles 20 and terminate short of the forward edges of said baffles 20. Member 24 is further formed with a plurality of vertical through openings 30 parallel to front wall 27 and communicating with the upper wall 28 and the lower edge 26.

Satisfactory results have been obtained in plating large record surfaces when the through openings 30 were $\frac{1}{16}$ " in diameter and spaced about $\frac{3}{8}$ " from each other.

In contact with the lower horizontal edge 26 of member 24, is the upper surface of a rectangular bar 31, of rectangular cross-section and of the same thickness and composition as member 24. Bar 31 which protrudes slightly from both sides 29 of member 24 is secured to member 24 by screws 32 or any other suitable means. Bar 31 is further formed in its upper surface with a vertical groove 33, which communicates with the through openings 30 of member 24, and which terminates short of the ends of said bar 31. A round through passage 34 communicates with groove 33 and one end surface of bar 31. Inserted into the through passage 34 and extending beyond the end surface of bar 21 is a chemically and electrically inert tube 35 for the purpose hereinafter described.

Electrical contact must be made between the negative terminal of a source of direct current, and the cathode or surface to be plated. To this end there is provided a heavy contact holder 36. Contact holder 36 comprises a bar of metal, preferably copper, of rectangular cross-section, having a vertical portion 37 extending upwardly along rear wall 13 from a point just below the center of backplate 11 to a point above the upper edge 14 of backplate 11. Extending from the upper end of vertical portion 37 and making an angle of about 135° therewith is a smaller rearwardly and upwardly inclined portion 38. Portion 38 is formed with a through opening 39 at its center for the purpose to be hereinafter described. Extending from the upper end of portion 38 in a downwardly and rearwardly direction, making an angle of 90° therewith is a portion 40. It will now be seen that portions 38 and 40 form a hook-like structure adapted to engage a cathode bar of square cross-section for an electrical connection. Vertical portion 37 is further formed with a round hole 41 spaced from its lower extremity, and in register with hole 18a in backplate 11.

By means of wing nut 67 the whole assembly is held rigid so that the vertical stream of air bubbles rises parallel to the surface of the record, agitating the solution in contact therewith but not actually making contact with the record surface.

To connect contact holder 36 with the record surface to be plated there is provided a rod 42, externally threaded at both ends, snugly inserted into holes 41 and 18a. The forward flat end of rod 42 is flush with front wall 12 of backplate 11. The rear flat end of rod 42 projects beyond vertical portion 37 of contact holder 36 and is secured thereto by nut 43 in threaded engagement with rod 42. An internally threaded disc-like

metal insert 44, having a flat front surface flush with front wall 12 of backplate 11 and adapted to snugly fit into recesses 17 and 18 of backplate 11, is threadedly engaged with the front external threads of rod 42. Rod 42 is further formed with an axially threaded opening 45 in its front end to receive a headed screw 46 for the purpose hereinafter described.

To prevent the formation of nodules, trees and roughness around the edges of the record to be plated, particularly when high current densities are used, there is provided a rectangular metallic sheet 47, preferably of aluminum, which lies flat against front wall 12 of backplate 11, and in contact with the front flat surface of insert 44.

Aluminum sheets of between .005" to $\frac{1}{16}$ " have been found to produce satisfactory results. The bottom edge of sheet 47 rests on the upper edge of the spacer bar 21 and covers substantially the entire front wall 12 of backplate 11, terminating just short of the sides and top thereof. Sheet 47 is formed with an opening 48 at its center to register with opening 45 in rod 42 and through which screw 46 passes. A metal washer 49 may be placed against the head of screw 46. The record 50 to be plated is interposed between the washer 49 and sheet 47 with the screw 46 passing through the hole 51 in the record 50. The record surface to be plated is the front surface 52.

All of the metal parts through which the plating current will flow are preferably made of copper, with the exception of sheet 47 which may be of aluminum, to provide a good conductor for the electric current. All the metal parts, with the exceptions of the surface to be plated and sheet 47 which come in contact with the plating solution or electrolyte in the plating tank should be painted or coated with a chemically and electrically inert material in order to prevent chemical and electrical reactions with the electrolyte.

It will now be understood that an electrical connection is made between the metallized cathode surface 52 of record 50 and contact bar 36 through washer 49, screw 46, sheet 47, insert 44, rod 42, nut 43 and vertical portion 37 of contact bar 36. Portions of the cellulose acetate film on record 50, near the center hole 51 may be scraped away to expose a metal base to insure a good electrical contact between washer 49 and sheet 47 when screw 46 is tightened.

For a better understanding of the plating process, reference is made particularly to Figs. 4 and 5 in which 53 designates a plating tank or container. Tank 53 is filled to capacity with the usual plating solution or electrolyte 54 which may be a solution of copper sulphate and sulfuric acid if, for instance, the stamper is to be made of copper. While stampers may be made of other metals, as for example nickel, the process of making copper stampers by this invention will be described for purposes of illustration. Two plating devices 19 are shown within tank 53 to illustrate the compactness and simplicity possible in this method of plating.

The anodes 62 may be placed as closely to the cathode surface as is practicable which by virtue of the construction is about 2". There are several advantages accruing to this close spacing. One important advantage is the low solution IR drop with its resultant saving in electrical power. Another advantage is to be seen in the effect of the air stream in agitating the solution in proximity to the anode surface thus reducing anode

polarization and any tendency toward sludge formation.

Tank 53 comprises a substantially square bottom wall 55, parallel side walls 56, a front wall 57 and a rear wall 58. Extending outwardly from the upper horizontal edges of side walls 56, front wall 57 and rear wall 58 is a square horizontal flange 59. Resting on electrical insulating blocks 59a on flange 59 and parallel to side walls 56 are two metal anode bars 60 each equally spaced from a side wall 56 of tank 53. Anode bars 60 may be of round or square cross-section and are preferably made of copper to act as good conductors of electricity. Suspended from each anode bar 60 by means of hooks 61 are two rectangular copper bars 62 which are the sources of metal used for plating the stamper. Anode bars 60 are electrically connected to a common anode terminal 63 as at 64 for the purpose of supplying a source of direct current to the plating solution 54.

Midway between anode bars 60 and parallel thereto are two adjacent cathode bars 65 which act as supports for the plating devices 10. Cathode bars 65 may be of square cross-section so that they may rest on their edges on flange 59. Extending upwardly and outwardly from each cathode bar 65 at its midpoint is a threaded shank 66. Plating device 10 is hung on cathode bar 65 so that shank 66 protrudes through opening 39 of cathode holder 36. Wing nut 37 is then screwed on shank 66 to make good electrical contact between the cathode holder 36 and the cathode bar 65. Cathode bars 65 are connected to a common cathode terminal 68 as at 69 for connection to the negative terminal of a direct current supply.

A chemically inert flexible rubber tube 70 is connected to tube 35 in member 31 for the purpose of supplying air under pressure from an air compressor blower through groove 33, openings 30 and over the metallized cathode surface 52 of the record 50 during the plating process.

To make a copper stamper of the metallized cathode surface 52 of the record 50, a source of direct current is applied across anode terminal 63 and cathode terminal 68. A copper pre-plate at a low current density of about 25 amps./sq. ft. is formed on the metallized cathode surface 52, until the thickness of the copper plate is of approximately 0.0005" to 0.001". It will be noted that during the entire plating process copper will also be deposited on the aluminum sheet 47 which extends beyond the periphery of record 50, and which is electrically connected to the negative source of direct current.

Air under pressure is next introduced through tube 70 and flows through passage 34, groove 33, openings 30 and over the metallized surface 52 being plated. The air uniformly agitates the plating solution along the whole plating surface. By varying the air pressure in tube 70 any degree of agitation of the plating solution, from mild to extremely violent, may be produced. By using strong agitation comparatively high current densities can be used and thus permit rapid electrodeposition to take place. Because of this uniform agitation over the face of the metallized cathode surface 52 the metal electrodeposited is smooth, uniform and of excellent physical characteristics for record stampers.

The aluminum sheet 47 serves the function of preventing excessive current density around the periphery of record 50. This is accomplished by extending the metallized cathode surface 52 on to plate 47 and causing the copper to plate onto

both aluminum sheet 47 and metallized cathode surface 52. The net effect of the assembly of the plating device 10 is to provide very uniform current distribution over the whole metallized cathode surface 52 of the record 50 with the result that the thickness of the electroformed shell or stamper from the center to the periphery is substantially uniform. Furthermore, the tendency for nodules, trees and roughness to occur over the surface being plated and particularly around the periphery of the record 50, is practically eliminated. This smoothness and uniformity is a decided advantage since, as previously pointed out, a single trimming cut on a lathe of a few thousandths is all that is required to produce a satisfactory finished stamper ready for use. In electroforming the copper shell or stamper current densities as high as 200 amps./sq. ft. may be employed with an air pressure of about 3 lbs. until a stamper shell of 0.050" is formed. Excellent results have been achieved in building up the requisite thickness of a stamper in from 6 to 10 hours by this method.

The baffles 20 and inclined wall 28 of member 24 of plating device 10 serve the function of preventing the current from concentrating along the edges of the metallized cathode surface 52 and the edges of sheet 47 thus eliminating any tendency toward the formation of trees and nodules which, as is well known in the art, are wasteful of metal and electrical energy, particularly when heavy electroplates are built up.

In Figs. 6, 7 and 8 is shown another embodiment of a plating device 110 similar to the plating device 10 shown in Figs. 1, 2 and 3, except for the arrangement of the baffles and the elimination of the metal sheet 47 behind the metallized cathode surface 52 of the record 50 to be plated. The plating device 110 comprises a rectangular prismatic-shaped support or backplate 111 of the same plate material as backplate 11. Said backplate 111 further comprises a front wall 112, a rear wall 113, a top edge 114, a bottom edge 115 and side edges 116. At substantially the center of backplate 111 are the same concentric dist-shaped recesses 17 and 18 and hole 18a as are formed in backplate 11.

A system of baffles is attached to backplate 111 for the purpose of directing the electrodeposited metal uniformly on the stamper to be formed and thereby prevent the formation of trees and nodules which usually form around the periphery of the stamper. To this end there are provided a pair of rectangular spacer plates 119, parallel to each other, and each adjacent and co-extensive with side edges 116 of backplate 111.

Plates 119 are of the same material as backplate 111, are perpendicular to front wall 112 of said backplate 111 and attached thereto by any suitable means. Attached to the front edges of plates 119 by any suitable means is a rectangular baffle 120 parallel to backplate 111, of the same chemically and electrically inert material, and coextensive therewith. Baffle 120 is formed with a large round hole 120a concentric with dist-shaped recesses 17 and 18, and hole 18a. Hole 120a is of slightly smaller diameter than the metallized cathode surface 52 of the record to be plated.

Flush with the lower edge 115 and on the front wall 112 of backplate 111 is a rectangular spacer bar 121. Spacer bar 121 is attached to backplate 111 by means of screws 123 or any other suitable means. The parallel side edges of spacer bar 121 terminate short of the inner surfaces of

plates 119 thereby forming a rectangular through opening 121a for the purpose of permitting drainage of electrolyte when device 110 is removed from the plating bath. Spacer bar 121 is made of the same material as backplate 111.

To provide strong agitation of the plating solution by supplying a steady stream of air bubbles through the plating solution and adjacent the cathode surface to be plated, there is provided a prismatic-shaped member 124 similar in function to member 24 of plating device 10. Member 124 is made of the same material as backplate 111 and comprises a rear wall 125 contacting the front wall of spacer bar 121 and extending beyond the side edges thereof, a lower horizontal wall 126 flush with the lower horizontal edge of spacer bar 121, a front wall 127 parallel to rear wall 125, and an upper wall 128 parallel to lower wall 126 and flush with the upper horizontal edge of spacer bar 121. The parallel side edges of member 124 contact the inner surfaces of plates 119. Member 124 is further formed with a plurality of vertical through openings 130 parallel to front wall 127 and communicating with upper wall 128 and lower wall 126, similar to openings 30 in member 24 of plating device 10. Member 124 may be secured to spacer bar 121 by screws 123 or any other suitable means.

In contact with and suitably attached to the lower horizontal wall 126 of member 124 and the lower edges of plates 119 is the upper surface of a rectangular prismatic bar 31. Bar 31 has the same construction and function in relation to member 124 of plating device 110 as it has in relation to member 24 of plating device 10. Interposed between and suitably attached to baffle 120 and the upper portion of front wall 127 is a spacer bar 131.

It will now be understood that a continuous stream of air under pressure from an air compressor can be introduced through tube 35, passage 34, groove 33, openings 130 and over the metallized cathode surface 52 of record 50 during the plating process.

In plating device 110 the rear surface of record 50 is placed flush against front wall 112 of backplate 111 and secured thereto in the same manner as record 50 is secured to plating device 10. It will be noted, however, that in plating device 110 there is no metal plate interposed between the back of the record 50 and the front wall 112 of the backplate 111.

It will now be understood that an electrical connection is made between the metallized cathode surface 52 of record 50 and contact bar 36 through washer 49, screw 48, insert 44, rod 42 and nut 43.

Plating device 110 can now be suspended into tank 53 in the same manner as plating device 10 and metallized cathode surface 52 of record 50 can now be plated to electroform a stamper as previously described. It will be noted however that in plating device 110 the entire cathode surface plated is the metallized cathode surface 52 of record 50. In plating device 10, the entire cathode surface plated is the metallized cathode surface 52 of record 50 and the portions of metal sheet 47 that extend beyond the periphery of record 50.

Baffle 120a functions to prevent an excess of metal from depositing around the periphery of the stamper. This is accomplished by diverting the metal ions in the plating solution from the periphery of the record because in travelling from the anode bars 62 to the metallized cathode surface 52, said ions must pass through hole 120a 70

which has a smaller diameter than said metallized cathode surface.

Referring now particularly to Figs. 9, 10 and 11, the record or electrical transcription to be plated is represented by numeral 50. Record 50 comprises a metal base 51a, usually of aluminum, a bottom side 51b, usually of a plastic material such as cellulose acetate, and a top side 51c also of a similar plastic material. Sound recordings are cut into the top side 51c, for instance, by a recording machine well known in the art. These recordings are in the form of grooves 51d. In order to make a stamper of these grooves 51d the entire surface 51c is metallized by a very thin coating of metal, usually in the form of a silver mirror or metallized cathode surface 52.

In the plating process the stamper 52a usually of copper, is deposited on the metallized cathode surface 52. When stamper 52a is of the required thickness it is pried loose from the record surface 51c. Stamper 52a, with the thin metallized surface 52 adhered to it now contains an impression of the sound recording made on the record and is capable of functioning as a die to stamp out similar recordings. By using the above plating devices and methods a stamper of substantially uniform thickness, an excellent stamping characteristic, is produced.

If desired a metallic sheet like sheet 47 may be employed in the apparatus shown in Figures 6, 7 and 8, interposed between the record 50 and the front wall 112 of backplate 111.

While the above specification has described the invention with relation to a metallized matrix surface of a plastic or non-metallic record or matrix, it is understood that the inventive method may be applied to a metal matrix surface also.

It will thus be seen that there are provided devices and processes in which the several objects of this invention are achieved and which are well adapted to meet the conditions of practical use.

As various possible embodiments might be made of the above invention, and as various changes might be made in the above embodiment set forth, it is understood that all matter herein set forth or shown in the accompanying drawings is to be interpreted as illustrative and not in a limiting sense.

I claim:

1. A device for plating the front metallized surface of a phonograph record comprising a backplate, a cathode holder attached to the back of said backplate, said cathode holder having means on one end to electrically contact a negative bus bar of a source of direct current, and means at the other end to make electrical contact through said backplate with said metallized surface of said phonograph record, means in the front of said backplate to hold the rear surface of said phonograph record in contact with the front surface of said backplate, and means near the bottom of said backplate to direct a stream of air bubbles adjacent to said metallized surface, and a baffle supported by said holder and disposed in front of and spaced from said record, said backplate and baffle being made of electrical insulating material resistant to plating solution.

2. A device for plating the front metallized surface of a phonograph record comprising a backplate, a cathode holder attached to the back of said backplate, said cathode holder having means on one end to electrically contact a negative bus bar of a source of direct current, and means at

the other end to make electrical contact through said backplate with said metallized surface of said phonograph record, means in the front of said backplate to hold the rear surface of said phonograph record in contact with the front surface of said backplate, means near the bottom of said backplate to direct a stream of air bubbles adjacent to said metallized surface, said last means comprising a member attached to the backplate and having a plurality of vertical through openings parallel to each other, and a bar attached to the underside of said member, formed with a longitudinal groove in its upper surface and communicating with said through openings and with a through passage at one end of said bar to receive air from an air compressor, a baffle attached to said member and disposed in front of and spaced from said backplate and having an opening opposed to said record, said backplate member, bar and baffle being made of electrical insulating material resistant to plating solutions.

3. A device for plating the front metallized surface of a phonograph record comprising a backplate, a cathode holder attached to the back of said backplate, said cathode holder having means on one end to electrically contact a negative bus bar of a source of direct current, and means at the other end to make electrical contact through said backplate with said metallized surface of said phonograph record, means in the front of said backplate to hold the rear surface of said phonograph record in contact with the front surface of said backplate, means near the bottom of said backplate to direct a stream of air bubbles adjacent to said metallized surface, and a baffle attached to said backplate and located in front of and spaced from said metallized surface, said baffle being formed with a circular hole of smaller diameter than the diameter of said metallized surface, said backplate and baffle being made of electric insulating material resistant to plating solution.

4. A plating device for electroforming stampers for phonograph records comprising a backplate, a cathode holder attached to the back of said backplate, said cathode holder having means on one end to make electrical contact with a negative bus bar, and means on the other end to make electrical contact through said backplate with a metallized cathode surface of phonograph record, means in the front of said backplate to hold said phonograph record against said backplate, and a baffle attached to said front of said backplate, said baffle being spaced from said backplate and metallized cathode surface, and formed with a circular hole having a smaller diameter than said metallized cathode surface of said phonograph record and concentric therewith, whereby the plating current is prevented from concentrating around the periphery and the formation of nodules, trees and roughness prevented around the periphery of said metallized cathode surface, said backplate and baffle being made of electric insulating material resistant to plating solutions, and means to supply air under pressure between the metallized surface and baffle.

5. A device for plating the front metallized surface of a phonographic record in a plating tank provided with a negative bus bar of a source of

direct current, said device comprising a unit which may be hung on the bus bar to project down into plating solution in the tank, said unit comprising a cathode holder having means at its upper end for removable attachment to said negative bus bar, means on said holder to support a phonograph record having a front metallized surface and to make electrical contact with the metallized surface of said phonograph record, a baffle plate of electric resistant material supported by said holder bar in spaced relation in front of the phonograph record, said baffle being formed with an opening in opposed relation to the record, and means supported by said holder to direct spaced streams of air bubbles adjacent said metallized surface and between the record and baffle, said unit being removable as a whole from the bus bar.

6. The device of claim 5 in combination with a backing plate of electrical resisting material, supported on the holder and against which the back of the record contacts.

7. A portable unitary device for plating the front metallized surface of a phonograph record, comprising a cathode holder having a hook at its upper end from which it may be hung on the negative bus bar of a plating tank, a record having a front metallized surface, means on the holder bar to support said record on a horizontal axis and to make electrical contact with the front metallized surface of said record, a baffle of electrical resistant material supported by said holder bar and disposed in front of the record in spaced relation thereto and being formed with an opening substantially coextensive with the metallized surface of said record whereby current in the plating tank is directed through the opening to said metallized surface, means supported by said holder bar and located between the lower end of the baffle and the record to direct upwardly, streams of air bubbles to agitate the plating solution in the tank, said device being removable from the tank as a unit by unhooking the holder bar from the bus bar.

8. The device of claim 7 in combination with a backing plate of electrical resistant material contacting the back of the record and supported on said holder.
